LIFTER

Edward V. Cullen, Erard J. Shaughnessy, and Charles J. Tupy, Chicago, Ill., assignors to Cullen-Friestedt Company, Chicago, Ill., a corporation of Illinois

Application March 30, 1940, Serial No. 326,922

16 Claims. (Cl. 294—117)

The present invention relates generally to lifters for handling stacks of sheets. More particularly the invention relates to that type of sheet lifter which is adapted to be hoisted and moved from place to place by a crane or overhead hoist and as its principal or essential parts comprises: (1) an elongated supporting element which is designed or adapted normally to extend horizontally and has an upstanding loop or other means on the central portion thereof whereby it may be attached to a hook or other connecting device on the operating end of the crane or hoist with which the lifter is used; (2) a pair of opposed complementary jaws which are shiftable to and from one another into and out of engagement with the side margins of the sheets and consist of upper members which are pivotally connected to, and depend from, the supporting element, and lower members which are connected to, and depend from, the upper members and are provided at the lower ends thereof with means for underlying and supporting the side margins of the sheets; and (3) gear mechanism which is carried by the supporting element and operates in response to actuation thereof conjointly to shifting the jaws to or from one another.

One object of the invention is to provide a lifter of this type which is an improvement upon, and has certain advantages over and greater capabilities of use than, previously designed lifters of the same general character, including the lifter which is shown in and forms the subject matter of application for United States Letters Patent, Serial No. 207,682, filed May 13, 1938, by Erard J. Shaughnessy, now Patent 2,210,355.

Another object of the invention is to provide a sheet lifter of the type and character under consideration which is capable of being used effectively and efficiently in connection with closely positioned stacks of sheets by reason of the fact that the lower members of the jaws are L-shaped and have the upper ends of their vertical legs so journaled or mounted that the lower members may be turned bodily back and forth between an inoperative position wherein the lower or horizontal legs are longitudinally aligned with one another and extend in parallel relation with the supporting element, and an operative or sheet supporting position wherein such horizontal legs extend inwardly, i. e., at right angles to the supporting element.

Another object of the invention is to provide a sheet lifter of the last mentioned character in which each of the jaws is provided with novel

means for conjointly turning the L-shaped lower members thereof back and forth between their inoperative and operative positions.

Another object of the invention is to provide 5 a sheet lifter of the aforementioned type which includes pairs of compression spring assemblies which extend between the horizontally extending supporting element and the upper ends of the jaws and are so arranged that the springs thereof are placed under compression in connection with closing or inward shift of the jaws and operate in connection with opening or outward movement of the jaws to counteract or lessen the effect of gravity on the jaws and thus reduce the 10 load on the gear mechanism.

Another object of the invention is to provide 15 a sheet lifter of the type and character hereinbefore set forth which includes at the ends of the supporting element hooks for gripping the central portions of the end parts of the sheets and prevent sagging of the sheets in connection 20 with hoisting and movement of the lifter.

Another object of the invention is to provide 25 a sheet lifter of the last mentioned character in which the end hooks for preventing the sheets from sagging are connected to wire cables, the inner upper ends of which are anchored to spring retracted drums on top of the supporting element.

A further object of the invention is the provision 30 in connection with a lifter of the type under consideration, of novel means for releasing and locking the drums to which are anchored the wire cables for the end hooks.

A still further object of the invention is to 35 provide a sheet lifter which is generally of new and improved construction, embodies a compact arrangement of its operating parts and effectively and efficiently fulfills its intended purpose.

Other objects of the invention and the various 40 advantages and characteristics of the present sheet lifter will be apparent from a consideration of the following detailed description.

The invention consists in the several novel 45 features which are hereinafter set forth and are more particularly defined by claims at the conclusion hereof.

In the drawings which accompany and form a 50 part of this specification or disclosure and in which like numerals of reference denote corresponding parts throughout the several views:

Figure 1 is a side view or elevation showing a lifter embodying the invention with the end hooks thereof and the L-shaped lower members of the jaws in gripping or supporting relation with a stack of sheets;

Figure 2 is a plan view of the lifter illustrating in detail the arrangement and design of the means for locking and releasing the spring retracted drums to which are anchored the wire supporting cables for the end hooks;

Figure 3 is a view partly in side elevation and partly in vertical section illustrating the manner in which the upper ends of the vertical legs of the L-shaped lower members of the jaws are journaled or rotatably mounted and disclosing the construction of the means for conjointly turning the lower members back and forth between their operative and inoperative positions;

Figure 4 is a vertical transverse section taken on the line 4—4 of Figure 1 and illustrating the design and arrangement of the pairs of spring assemblies for counteracting the effect of gravity on the jaws in connection with jaw opening actuation of the gear mechanism;

Figure 5 is a side view of one of the spring retracted drums, parts being broken away for purposes of illustration; and

Figure 6 is a vertical transverse section on the line 6—6 of Figure 5.

The lifter which is illustrated in the drawings constitutes the preferred embodiment of the invention. It is adapted in connection with a crane or overhead hoist having a hook at its operating end, to lift or move from one place to another a stack of sheets or like articles, and comprises an elongated supporting element 7, a pair of opposed complementary jaws 8 and 9, and a gear mechanism 10 for conjointly opening and closing the jaws, i. e., shifting the jaws to and from one another.

The supporting element 7 is adapted normally to extend horizontally. It carries the jaws 8 and 9 as well as the gear mechanism 10 and is in the form of an I-beam. As shown in the drawings, the element 7 carries the jaws in a depending manner and comprises a vertical web 11, a horizontally extending top flange 12 and a horizontally extending bottom flange 13. An upstanding loop 14 for the hook at the operating end of the crane or hoist with which the lifter is used, is suitably secured to the central portion of the element 7. This loop is so positioned with respect to the ends of the element 7 that the lifter as a whole balances and assumes substantially a horizontal position when it is hoisted or moved from place to place.

The jaws 8 and 9 are adapted, as hereinafter described, to be shifted to and from one another in response to actuation of the gear mechanism 10. They extend lengthwise of the supporting element and comprise upper members 15 and lower members 16. Each of the jaws, as shown in the drawings, embodies a plurality of upper members and a corresponding number of lower members. The upper members 15 have inturned or inwardly extending upper ends and each is composed of a pair of laterally spaced plate metal pieces 17. The upper ends of the upper members of the jaws are pivotally connected by way of pivot pins 18 to pairs of outwardly extending laterally spaced pivot lugs 19 on the supporting element 7. The upper members 15 of the jaw 8 are positioned in opposed relation with the upper members of the jaw 9. The pairs of pivot lugs fit between, and are welded or otherwise fixedly secured to, the top and bottom flanges of the element 7 and project into the intervening spaces at the upper ends of the pairs of pieces 17 which form or constitute the upper jaw members 15. The pins 18 extend through aligned

holes in the pivot lugs and the upper ends of the pieces 17 and together with the lugs 19 so pivotally support the jaws 8 and 9 that the latter are free to swing to and from one another into and out of gripping relation with a stack of sheets. The lower members 16 of the jaws are L-shaped and consist of elongated vertically extending legs 20 and short horizontally extending legs 21. The horizontal legs 21 are formed integrally with, and extend at right angles to, the lower ends of the vertical legs 20. When the lower members 16 of the jaws are in their normal or operative position the legs 21 extend inwards so that they are adapted to underlie the sheets to be lifted (see Figure 4). Preferably the top faces of the horizontal legs 21 are flat. The vertical legs 20 of the lower members of the jaws are provided with reduced stems 22 and these extend through, and are journaled in, box-like housings 23 in order that the lower members may be turned as hereinafter described, from their operative position wherein the horizontal legs 21 extend or face inwards, to an inoperative position wherein said legs 21 are longitudinally aligned and extend in parallel relation with the supporting element 7. The housings 23 fit within the intervening spaces at the lower ends of the pairs of plate metal pieces 17 and consist of side walls 24, top walls 25 and bottom walls 26. The top and bottom walls fit between, and are suitably secured to, the side walls and serve to hold the latter in laterally spaced relation. The lower members 16 of the jaws are connected to the upper members 15 by way of a pair of shafts 27 in order that they may be swung into different angular positions with respect to the upper members and thus adapt the lifter for use in connection with stacks of wide sheets as well as small sheets. The shafts 27 are associated with the jaws 8 and 9, respectively, and extend horizontally. They are positioned in parallel relation and extend loosely through holes 28 in the side walls 24 of the housings 23 and holes 29 in inwardly extending lugs 30 at the lower ends of the plate metal pieces 17. As shown in Figure 3, the holes 28 and 29 are coaxial. The side walls 24 of the housings 23 are sector shaped and have at the top thereof arcuate series of notches 31. The latter are positioned above the shafts 27 and coact with a pair of horizontally extending slide bars 32 to form means for holding the lower members 16 of the jaws 8 and 9 in their various adjusted positions with respect to the upper members 15. The bars 32 are associated with the two jaws respectively and are positioned above the shafts 27 and directly over the box-like housings 23. They are mounted for longitudinal sliding movement in slots 33 in the lower central portions of the pieces 17 and have notches 34 in the bottom portions thereof. Said notches 34 are normally located to one side of the side walls 24 of the housings 23, as shown in Figure 3 of the drawings, and are adapted when the bars 32 are shifted in one direction, to be brought into registry with the notched arcuate top portions of said side walls 24 and release the housings as far as the bars are concerned so that the lower members 16 of the jaws are free to be swung laterally into different angular positions relatively to the upper members 15 of the jaws. The portions of the bars 32 which are adjacent to and define the notches 34, constitute locking dogs 35. The latter are adapted, when the locking bars are shifted in the opposite direction after proper adjustment of the lower members 16 with respect to the up-

per members 15, to fit within the adjacent notches 31 of the side walls of the housings 23 and thus lock the lower members of the jaws in fixed or set relation with the upper members 15. Longitudinal shift of the bars 32 is effected by means of a pair of levers 36. The latter are located at one end of the lifter and are pivotally connected to certain of the pieces 17. Links 37 connect the levers 36 to the adjacent ends of the slide bars 32 with the result that when the levers are swung in one direction they slide the bars into a position wherein the lower members of the jaws are released for angular adjustment with respect to the upper members and when the levers are swung in the other direction they so shift the bars as to effect locking of the lower members in their adjusted positions with respect to the upper members of the jaws. The lower members 16 of the jaws are confined against vertical displacement with respect to the box-like housings 23 by means of enlarged shoulders 38 at the lower ends of the stems 22 and nuts 39 at the upper ends of the stems. The shoulders 38 abut against the bottom faces of the bottom walls 26 of the housings 23 and the nuts 39 overlie the top faces of the top walls 25 of the housings. The nuts and shoulders are so spaced apart that they do not interfere with turning of the lower jaw members 16 about the axes of the vertical legs 20. In order to effect conjoint turning of the lower jaw members back and forth between their aforementioned operative and inoperative positions pairs of spiral toothed gears 40 and 41 are provided. The gears 40 are keyed or otherwise fixedly secured to the shafts 27 and are disposed between the side walls 24 of the boxlike housings 23. The gears 41 are suitably fixedly secured to the reduced stems 22 at the upper ends of the lower jaw members 16 and are in mesh with the gears 40. When the shafts 27 are properly turned the lower members 16 are turned by the action of the gears 40 and 41 from their operative position wherein the horizontal legs 21 extend inwardly, to their inoperative position wherein such legs are longitudinally aligned and are positioned in parallel relation with the supporting element 7. When the shafts 27 are reversely turned the lower jaw members 16 are turned from their inoperative position to their operative position. By providing means whereby the lower jaw members may be conjointly turned from their normal or operative position into an inoperative position wherein the horizontal legs 20 are longitudinally aligned it is possible to use the lifter in connection with closely positioned stacks of sheets. When the stack to be lifted is positioned in close proximity to other stacks at the sides thereof the operator of the lifter turns the lower jaw members into their inoperative position and then lowers the lifter into straddle relation with the stack to be lifted. Thereafter the lower jaw members 16 are turned into their operative position by proper turning or manipulation of the shafts 27. After such turning of the shafts the jaws are swung inwards into gripping relation with the sides of the stack to be lifted by proper actuation of the gear mechanism 10. In order to permit the operator of the lifter readily to turn the shafts 27 each of the shafts is provided with a radially extending turning lever 42. As shown in Figure 1 the levers 42 are positioned at one end of the lifter and are provided at their distal ends with hand grips 43. When it is desired to rotate shafts 27 the operator grasps the grips 43 and by swinging the levers 42 effects, 75

through the medium of the spirally toothed gears 40 and 41, turning of the lower jaw members 16. The levers 42 are provided with locking dogs 44 for releasably holding them in place. These dogs have the central portions thereof pivotally connected to the inner or proximal ends of the levers 42 and are adapted to coact with peripherally notched discs 45 which are fixedly secured to the plate metal pieces 17 that carry the slide bar actuating levers 36. The inner ends of the dogs 44 are designed to fit within the notches of the discs 45 and when in place lock the shafts 27 against rotation. Release of the dogs 44 is effected by means of plungers 46. The latter are pivotally connected to the outer ends of the dogs 44 and extend through and are mounted slidably within the grip equipped distal ends of the levers 42. The outer ends of the plungers are provided with finger pieces 47 adjacent the outer ends of the grips 43. Compression springs 48 around the plungers and within the grips urge the plungers outwards and thus operate to hold the dogs 44 in locked relation with the discs 45. When it is desired to release the dogs 44 in connection with turning of the shafts 27 it is only necessary to press the finger pieces 47 inwards. This serves to slide the plungers 46 inwards and swing the dogs 44 out of locked relation or engagement with the discs 45. When the finger pieces 47 are released the springs 48 operate through the medium of the plungers 46, to swing the dogs 44 into locked relation with the discs. The levers 42, the shafts 27 and the spiral toothed gears 40 and 41 constitute or exemplify simple means for conjointly shifting the lower jaw members 16 back and forth between their operative and inoperative positions. The locking dogs 44, the peripherally notched discs 45 and the plungers 46 constitute simple means for releasably locking the shafts 27 in the various positions into which they are turned or rotated.

The gear mechanism 10 for conjointly shifting or swinging the jaws 8 and 9 to and from one another comprises a hand wheel 49, a pair of shafts 50 and 51, a brake unit 52, a gear unit 53, a pinion 54, a gear segment 55, a shaft 56 and sets of arms 57 and 58. The shaft 50 extends longitudinally of the lifter and is located beneath what may be termed or considered the front end of the supporting element 7. It carries the hand wheel 49 at its outer or front end and is journaled in a pair of bearing brackets 59 which depend from plate 60 at the front end of the supporting element 7. As shown in Figure 1, the plate 60 is fixed to the front end of the bottom flange 13 of the supporting element 7 and projects forwardly beyond the front end of the element. The brake unit 52 is located beneath and is connected by way of a bracket to the central portion of the flange 13 and includes drive and driven parts (not shown). The drive part of the unit 52 is connected to the inner end of the shaft 50 through the medium of the shaft 51. The driven part of the unit operates to drive the gear unit 53. The latter is mounted beneath the rear end of the element 7 and includes a driven shaft to which is fixed the pinion 54. The shaft 56 underlies the supporting element 7 and is journaled in bearing brackets 61. The gear segment 55 is fixed to the shaft 56 and is in mesh with and adapted for drive by the pinion 54. When the hand wheel 49 is rotated or turned in one direction the shafts 50 and 51, the brake unit 52, the gear unit 53, the pinion 54 and the gear segment 55 operate to rock or turn the shaft 56 in

one direction and when the hand wheel is rotated in the reverse direction the aforementioned operating parts cause reverse rocking or turning of the shaft 56. The arms 57 are fixed to and radiate from the shaft 56 and are transversely aligned with the upper members 15 of the jaws. They correspond in number to the upper members 15 of the jaw 8 and are connected to such members by way of links 62 and operate in response to rocking or rotation of the shaft 56 in one direction to swing the jaw outwards and in response to reverse rotation of the shaft to swing said jaw 8 inwards. The arms 58 radiate from the shaft 56 and are transversely aligned with the upper members of the jaws. They correspond in number to the upper members of the jaw 9 and are connected to such members by links 63. The arms 57 and 58 together with their respective links 62 and 63 are so arranged that rocking or turning of the shaft 56 in one direction effects conjoint opening of the jaws 8 and 9 and reverse rocking or rotation of the shaft effects conjoint closing or inward swing of the jaws.

In order to offset or counteract the action or effect of gravity on the jaws 8 and 9 pairs of upstanding compression spring assemblies 64 and 65 are provided. These assemblies are associated with the jaws 8 and 9 respectively, as shown in Figure 4. The assemblies 65 are preferably four in number and these are arranged two in straddle relation with the front upper member of the jaw 9 and two in straddle relation with the rear-most upper member of the jaw 9. As shown in Figure 4, the assemblies 65 comprise rods 66, sleeves 67 and compression springs 68. The upper ends of the rods are pivotally connected to horizontally extending stub shafts 69 in order that the assemblies are free to swing or move laterally, i. e., in a transverse direction with respect to the horizontal supporting element 7. The stub shafts 69 are located above the top flange 12 of the element 7 and are carried by upstanding ears 70 in such manner that they are substantially vertically aligned with certain of the pivot pins 18 for the jaw 9. The ears 70 are welded or otherwise fixedly secured to the supporting element 7. The rods 66 fit slidably within the sleeves 67 and embody nuts 71 at their lower ends. The sleeves 67 surround all but the upper extremities of the rods and have ring shaped blocks 72 fixed within their upper ends. The upper ends of the rods extend through these blocks. Plugs 73 are fixed within and serve to close the lower ends of the sleeves 67. The lower ends of the sleeves of the two spring assemblies at the front end of the lifter are pivotally connected to the front upper member of the jaw 9 by way of a pivot pin 74. This pin extends through the central portion of said upper member and through the plug 73 in the lower ends of the sleeves of the two assemblies at the front of the lifter. The lower ends of the sleeves of the two assemblies 65 at the rear of the lifter are pivotally connected to the central portion of the rear-most upper member of the jaw 9 by way of a pivot pin 75. The compression springs 68 extend between the nuts 71 at the lower ends of the rods 66 and the blocks 72 in the upper ends of the sleeves 67. The spring assemblies 65 are so arranged that when the jaw 9 is swung inwards the compression springs 68 are placed under compression and when the jaw 9 is opened the assemblies 65, due to the compression of the springs 68, exert opening force upon the jaw 9 and thus counteract or lessen the effect of gravity on the jaw and reduce the load on the

gear mechanism 10. As shown in Figure 4, the spring assemblies 65 are so arranged that when the jaw 9 is in its fully closed position they are in dead center relation as far as the pivot pins 18 for the jaw 9 are concerned and hence they do not exert any opening force upon the jaw 9. The spring assemblies 64 correspond in design and function similarly to the assemblies 65. They comprise rods 76, sleeves 77 and compression springs (not shown) and are preferably four in number. Two of the assemblies 64 are positioned in straddled relation with the foremost upper member of the jaw 8 and the other two assemblies 64 are positioned or arranged in straddled relation with the rear-most upper member of said jaw 8. The upper ends of the rods 76 are pivotally connected to stub shafts 78 which are horizontally aligned with the stub shafts 69 and overlie and are vertically aligned with certain of the pivot pins 18 for the jaw 8. The lower ends of the sleeves 77 of the two foremost assemblies 64 are pivotally connected to the central portion of the foremost upper member of the jaw 8 by means of a pivot pin 79 and the lower ends of the sleeves of the two rear-most assemblies 64 are pivotally connected to the central portion of the rear-most upper member of the jaw 8 by a pivot pin 80. The springs of the assemblies 64 are placed under the same compression as the springs 68 and are adapted to be compressed in connection with closing of the jaw 8. When the jaw 8 is opened the assemblies 64 urge such jaw outwards and thus counteract or offset the action of gravity on the jaw and lessen the load on the gear mechanism 10. The assemblies 64 are so positioned or arranged that they are in dead center relation with the pivot pins 18 for the jaw 8 when such jaw is in its fully closed position, as shown in full lines in Figure 4. The assemblies 64 and 65 constitute simple means for counteracting the effect of gravity on the jaws 8 and 9 and materially facilitate opening of the jaws. It is to be particularly noted that whereas the compression springs of the spring assemblies 64 and 65 are under progressively decreasing compression as the jaws 8 and 9 swing outwards such assemblies exert increased outward force on the jaws because the pivotal arrangement is such that their leverage or toggle action increases in connection with increased outward swing of the jaws. Because of the specific spring arrangement of the spring assemblies the assemblies, except when they are in dead center relation with the pivot pins 18, exert substantially uniform outward thrust on the jaws regardless of the extent to which the jaws are opened.

In addition to the supporting element 7, the jaws 8 and 9 and the gear mechanism 10 the lifter comprises a pair of end hooks 81 and 82. These hooks, as hereinafter described, serve to prevent sagging of the central portions of the sheets when the lifter is charged or loaded and moved from place to place. The hook 81 is located at the front end of the lifter and is C-shaped. It is provided with a handle 83 for manipulating purposes and is connected to a spring retracted drum 84 by a wire cable 85. The drum 84 is mounted over the central portion of the supporting element 7. The cable 85 is suitably connected to the upper end of the hook 81 and extends over a sheave 86 on the front end of the element 7. The drum 84 is rotatably mounted on a horizontally extending shaft 87 which extends transversely of the element 7 and is supported at its ends by a pair of bearing

brackets 88. The latter are secured to and project upwardly from the top flange 12 of the element 7. The drum 84 comprises a hub 89, a side wall 90 and a substantially cylindrical outer wall 91 and these are shaped on the exterior surfaces thereof to provide a spiral groove 92. The latter is of progressively increasing diameter and has the inner end of the wire cable 85 suitably anchored to its large end. The portion of the wire cable 85 adjacent the anchored inner end is wrapped around the groove 92, as shown in Figure 6. When the end hook 81 is pulled outwards the wire cable 85 unwinds first from the small end of the groove 92, then from the central portion and finally from the outer end of the groove. A convolute spring 93 serves to retract the drum 84, i. e., urge the drum in such direction as to cause the wire cable 85 to wind therearound. The inner end of this spring is anchored to a collar 94 on the shaft 87. The outer end of the spring is suitably secured to the inner periphery of the cylinder outer wall 91 of the drum. When the end hook 81 is pulled outwards the drum is so rotated that it winds up the spring 93. Upon release of the end hook 81 the spring 93 acts reversely to rotate the drum and thus winds up the wire cable 85. Because of the spiral groove 92 the force necessary to pull outwards the end hook 81 is uniform or constant. This is attributable to the fact that at the start of outward pull of the end hook 81 the spring 93 is under a minimum amount of tension. As the end hook 81 is moved progressively outwards and the spring 93 is resultantly placed under increased tension the wire cable 85, due to the spiral groove 92, moves farther from the center of the drum and hence affords greater leverage for rotation of the drum against the force of the spring. Such progressive leverage on the part of the cable, due to the spiral groove 92, compensates for increased resistance of the spring 93. A pawl 95 and coacting ratchet teeth 96 on the outer periphery of the outer wall 91 of the drum serve to lock the drum against rotation when the end hook 81 is hooked in place. The ratchet teeth are formed integrally with the outer wall 91 and are located at one side of the side wall of the spiral groove 92. The pawl 95 is rotatably mounted on a horizontally extending pin 97 which extends transversely of the supporting element 7 and is carried by one of the bearing brackets 88. It is adapted to swing into and out of mesh with the ratchet teeth 96 and is fixed to, and controlled by, an upstanding lever 98. The latter is centrally journaled or fulcrumed on the pin 97 and has a tension spring 99 between its upper end and a lug on the adjacent bearing bracket 88. The spring 99 urges the lever 98 in a clockwise direction, as viewed in Figure 5, and tends to maintain the pawl 95 in seated relation with the ratchet teeth 96. When the pawl is in such seated relation the drum 84 is locked against rotation and thus holds the end hook 81 in fixed relation with the sheets to which it is applied. The ratchet teeth 96 are so arranged that the drum 84 is at all times free to wind up the cable 85. When the lever 98 is turned or rotated in a counterclockwise direction, as viewed in Figure 5, the pawl 95 is swung out of seated relation with the ratchet teeth 96 and the drum 84 is thus released so that it is free to permit unwinding of the cable 85. The end hook 82 is disposed at the rear or opposite end of the lifter and is shaped like the end hook 81. It is adapted to be hooked onto the rear ends of the sheets to be lifted, as

illustrated in Figure 1, and is connected to a spring retracted drum 100 over the central portion of the supporting element 7 by way of a wire cable 101. The cable 101 is connected to the upper portion of the end hook 82 and passes over a sheave 102 on the rear end of the supporting element 7. The drum 100 is the same in construction as the drum 84 but is reversely positioned on the element 7. It has a spiral groove 103 upon which the upper or inner end of the cable 101 is wrapped. A pawl 104 and an annular series of ratchet teeth 105 on the outer periphery of the outer wall of the drum 100 serve to lock the drum against unwinding when the hook 82 is in place. The pawl 104 is rotatably mounted on a pivot pin 106 and is controlled by an upstanding lever 107. Such lever is centrally pivoted or fulcrumed on the pivot pin 106 and has a tension spring 108 applied to its upper end. Such spring urges the pawl 104 into meshing or seated relation with the ratchet teeth 105. When the lever 107 is turned clockwise, as viewed in Figure 1, the pawl 104 is swung out of engagement with the teeth 105 and the drum 100 is thus free for unwinding. The drum 100 has a convolute spring and this serves to rotate the drum in such direction as to wind up the cable 101.

In order that the operator may conjointly release the pawls 95 and 104 from the front end of the lifter a cable 109 and a cable 110 are provided. The cable 109 is anchored at one end thereof to the lower end of the lever 98, and leads forwardly around a sheave 111 and thence downwards. The sheave 111 is mounted on the front end of the plate 60. The lower end of the cable 109 is provided with a grip 112. When the grip 112 is pulled the cable 109 operates to swing the lever 98 in a counterclockwise direction, as viewed in Figures 1 and 5, and thus releases the pawl 95 from the ratchet teeth 96. The cable 110 is anchored at one end thereof to the lower end of the lever 107. The central portion of the cable 110 extends through a hole in the vertical web 11 of the supporting element 7 and around a pair of sheaves 113. Such sheaves, as shown in Figure 2, are located on opposite sides of the vertical web of the element 7. The other end of the cable 110 is anchored to the lower end of the lever 107. Said cable 110 so connects the two levers 107 and 98 that when the cable 109 is pulled to release the dog 95 from the ratchet teeth 96 the lever 107 is turned clockwise, as viewed in Figure 1, and releases the dog 104 from the ratchet teeth 105 on the drum 100. When it is desired to release the two drums so that the end hooks 81 and 82 may be pulled downwards and applied to the ends of a stack of sheets to be lifted by the lifter it is only necessary to pull on the grip 112. Such action, as heretofore described, operates conjointly to disengage the two dogs 95 and 104 from their respective ratchet teeth.

For the purpose of releasably locking the levers 98 and 107 in their open position, a latch device 114 is provided. This device comprises a latch dog 115 and a rotary latch plate 116. The latch dog extends substantially vertically and is centrally pivoted on a pivot stud 117 which is carried by and projects laterally from a bracket plate 118. As shown in Figure 5, at plate 118 extends between the top and bottom flanges of the supporting element 7 and fits against one side face of the vertical web 11. The upper end of the dog 115 is in the form of a hook and is

disposed adjacent to the rotary latch plate 116. The latter is rotatably mounted on a pivot stud 119 on the bracket plate 118 and has a notch 120 in its periphery. An arm 121 and a link 122 connect the latch plate to the lever 98 in such manner that the latch plate is rotated in response to swinging of said lever 98. The arm 121 is fixed to one side of and radiates from the ratchet plate. The link 122 extends between and is pivotally connected to the lower end of the lever 98 and the distal end of the arm 121. When the lever 98 is swung in a counterclockwise direction in connection with release of the drums 84 and 108 the latch plate 116 is rotated in one direction. A tension spring 123 is anchored to a lug 124 on the supporting element 7 and is connected to the lower end of the locking dog 115. This spring operates to urge the locking dog in a counterclockwise direction, as viewed in Figure 1, i. e., in such a direction that the hooked upper end of the lever bears against the periphery of the latch plate 116. The notch 120 is so positioned that when the lever 98 is swung into its open position by manipulation of the cable 109 it registers with the upper or hooked end of the dog 115. When the notch is in registry with the upper hooked end of the dog the spring 123 swings the dog into hooked relation with the notch and thus the dog together with the latch plate 116, the arm 121 and the link 122 holds the lever 98 as well as the lever 107 in open position. In order to permit the operator of the lifter to unhook the dog 115 from the latch plate a cable 124 and a cable 125 are provided. The cable 124 is connected to the upper or hooked end of the locking dog 115 and extends forwardly, thence around a sheave 126 on the plate 60 and thence downwards. The lower end of the cable 109 has a grip 127 so that the cable may be pulled by the operator. When such cable is pulled the latch dog 115 is swung out of engagement with the latch plate 116 and thus releases the levers 98 and 107 so that the springs 99 and 108 operate to swing them in such manner that they bring their respective pawls into engagement with the ratchet teeth 96 and 105. The cable 125 is connected to the lower end of the latch dog 115 and leads rearwardly to a sheave 128 and extends around the sheave and thence downwards. The sheave 128 is mounted on a plate 129 at the rear end of the supporting element 7. The lower end of the cable 125 is provided with a grip 130 whereby the cable may be pulled in order to disengage the latch dog 115 from the latch plate 116. The latch device 114 serves releasably to lock the levers 98 and 107 in their open position and is releasable from either end of the lever as the result of the provision of the cables 124 and 125.

The operation of the lifter is as follows: When it is desired to lift a stack of sheets the jaws 8 and 9 are opened to the proper extent by manipulation of the gear mechanism 10. Thereafter the lower members 16 of the jaws are turned into their inoperative position. This is accomplished by releasing the levers 42 and then swinging the levers so as to turn the shafts 27 in the proper direction. After the lower members 16 of the jaws have been shifted into their inoperative position the lifter is shifted or moved so as to bring the jaws 8 and 9 into straddled relation with the stack of sheets. Thereafter the lower members 16 of the jaws are turned into

their operative position by proper manipulation of the levers 42. After the last mentioned operation the gear mechanism 10 is manipulated so as to swing the jaws inwards. If it is desired to use the end hooks 81 and 82 the cable 109 is first pulled in order to swing the levers 98 and 107 into their open position. When the levers are in such position the latch 114 operates automatically to retain them in such position. Upon release of the pawls 95 and 104 from the ratchet teeth of the drums the drums are released and hence the operator of the lifter may pull the hooks 81 and 82 downwards and manipulate them into hooked relation with the ends of the stack of sheets. After proper manipulation of the hooks the latch device 114 is released by pulling either the cable 124 or the cable 125. Upon release of the device the pawls 95 and 104 move into seated relation with the ratchet teeth 106 and 105 and lock the drums in place. At the conclusion of this operation the lifter, together with the stack of sheets, is lifted and then moved to the desired location or place by manipulation of the crane or overhead hoist with which the lifter is associated. As soon as the proper location or place is reached the lifter is lowered and the gear mechanism 10 is then manipulated so as to open the jaws 8 and 9. In the event that it is desired to use the lifter in connection with a stack of comparatively wide sheets the lower members 16 of the jaws are released from the upper members by manipulating the levers 36 in such manner as to bring the notches 34 into registry with the upper notched portions of the side walls 24 of the box-like housings 23. Upon release of the lower members 16 they are angularly adjusted as desired and then locked in place by inward shift of the slide bars 32.

The herein described sheet lifter effectively and efficiently fulfills its intended purpose due to the specific construction and arrangement of its parts. Because the jaws embody rotatable L-shaped lower members the lifter may be used in connection with closely spaced stacks of sheets. The lifter is capable of quick and ready adjustment and is characterized by the fact that the end hooks 81 and 82 permit its use with a stack of comparatively wide sheets.

The invention is not to be understood as restricted to the details set forth since these may be modified within the scope of the appended claims without departing from the spirit and scope of the invention.

Having thus described the invention what we claim as new and desire to secure by Letters Patent is:

1. A lifter adapted for use in handling sheets and other articles and comprising a pair of opposed horizontally elongated jaws mounted to move to and from one another, one of said jaws embodying a plurality of upstanding laterally spaced and aligned L-shaped members having the upper ends thereof mounted rotatably so that said members may be turned back and forth between an operative position wherein the bottom legs thereof face inwards and an inoperative position wherein said legs are substantially longitudinally aligned, means for conjointly shifting the members of said one jaw back and forth between their operative and inoperative positions comprising a horizontal rotatable shaft extending lengthwise of said one jaw and carried by the latter adjacent the upper ends of the members and pairs of meshing gears between the shaft and

said upper ends of the members, and means for conjointly shifting the jaws to and from one another.

2. A lifter adapted for use in handling sheets and other articles and comprising a pair of opposed horizontally elongated jaws mounted to move to and from one another, one of said jaws embodying a plurality of upstanding laterally spaced and aligned L-shaped members having the upper ends thereof mounted rotatably so that the members may be turned back and forth between an operative position wherein the bottom legs thereof face inwards and an inoperative position wherein said legs are substantially longitudinally aligned, means associated with said one jaw for conjointly shifting the L-shaped members back and forth between their operative and inoperative positions comprising a horizontal rotatable shaft extending lengthwise of said one jaw and carried by the latter adjacent the upper ends of the members, pairs of meshing gears between the shaft and said upper ends of the members and a shaft turning or rotating lever disposed in one end of said one jaw and connected to, and projecting radially from, the adjacent end of the shaft, releasable latch means associated with the lever for locking said shifting means against actuation, and means for conjointly shifting the jaws to and from one another.

3. A lifter adapted for use in handling sheets and other articles and comprising a pair of opposed horizontally elongated jaws mounted to move to and from one another, one of said jaws embodying a plurality of upstanding laterally spaced and aligned L-shaped members having the upper ends thereof mounted rotatably so that the members may be turned back and forth between an operative position wherein the bottom legs thereof face inwards and an inoperative position wherein said legs are substantially longitudinally aligned, means for conjointly shifting the L-shaped members back and forth between their operative and inoperative positions comprising a rotatable horizontally extending shaft extending lengthwise of said one jaw and disposed adjacent the upper ends of said members and pairs of meshing spiral toothed gears between the shaft and the upper ends of the members, means for releasably locking the shaft against rotation, and means for shifting the jaws to and from one another.

4. A lifter adapted for use in handling sheets and other articles and comprising a pair of opposed jaws mounted to move to and from one another, one of said jaws embodying a plurality of laterally spaced and aligned depending upper members and in addition a corresponding number of upstanding L-shaped members associated respectively with the upper members and having the upper ends thereof rotatably mounted in housings so that they may be turned back and forth between an operative position wherein the bottom legs thereof face or project inwards and an inoperative position wherein said legs are at right angles to their normal or operative position, a rotatable horizontal shaft extending through the housings and the lower ends of the upper members for connecting the lower members to the upper members so that they may be angularly adjusted relatively thereto, means for releasably locking the lower members in their various adjusted positions, means for conjointly shifting the lower members back and forth between their operative and inoperative positions including said shaft and gearing between the

shaft and upper ends of said lower members, and means for shifting the jaws to and from one another.

5. A lifter adapted for use in handling sheets and other articles and comprising a horizontally elongated supporting element, a pair of opposed jaws depending from the sides of the element, one of said jaws being pivotally connected to the element so that it may be swung to and from the other jaw, means for swinging said one jaw to and from the other jaw, a compression spring assembly extending between the element and said one jaw and arranged so that the spring thereof is placed under compression in connection with inward swing of said one jaw and operates upon outward swing of said one jaw to counteract or lessen the effect of gravity on the one jaw.

6. A lifter adapted for use in handling sheets and other articles and comprising a horizontally elongated supporting element, a pair of opposed jaws depending from the sides of the element and pivotally connected to said element so that they may be swung to and from one another, means for conjointly swinging said jaws to and from one another, and compression spring assemblies extending between the element and the jaws and arranged so that the springs thereof are placed under compression in connection with inward swinging of the jaws and operate upon outward swing of the jaws to counteract or lessen the effect of gravity on the jaws.

7. A lifter adapted for use in handling sheets and other articles and comprising a horizontally elongated supporting element, a pair of opposed complementary jaws depending from the sides of the element and having the upper ends thereof connected by pivotal connections to the element so that they may be swung to and from one another, means carried by the element for conjointly swinging said jaws to and from one another, and a pair of upstanding compression spring assemblies having the upper ends thereof pivotally connected to the element above said pivotal connections and having their lower ends pivotally connected to the jaws, and arranged so that the springs thereof are placed under compression in connection with inward swing of the jaws and operate upon outward swing of the jaws to counteract or lessen the effect of gravity on the jaws, and further arranged so that when the jaws are swung inwards to substantially the fullest extent they are in dead center relation with said pivotal connections.

8. A lifter adapted for use in handling sheets and other articles and comprising a horizontally elongated supporting element, a pair of opposed complementary jaws depending from the sides of the element and connected to said element so that they may be swung to and from one another, gear mechanism carried by the element for conjointly swinging said jaws to and from one another, and means including compression springs between the element and the jaws for resisting inward swing of the jaws.

9. A lifter adapted for use in handling stacks of sheets and comprising a horizontally elongated supporting element, a pair of opposed jaws depending from the sides of the element and mounted to move to and from one another into and out of gripping relation with a stack of sheets, and means for supporting the central portion of the stack against sagging embodying an end hook, a supporting cable for the hook having one end thereof connected to said hook, and a spring retracted drum carried by the element and

having the other end of the cable attached thereto.

10. A lifter adapted for use in handling stacks of sheets and comprising a horizontally elongated supporting element, a pair of opposed jaws depending from the sides of the element and mounted to move to and from one another into and out of gripping relation with a stack of sheets, and means for supporting the central portion of the stack against sagging embodying an end hook, a supporting cable for the hook having one end thereof connected to said hook, a spring retracted drum carried by the element and having the other end of the cable attached thereto, and releasable mechanism for locking the drum against rotation.

11. A lifter adapted for use in handling stacks of sheets and comprising a horizontally elongated supporting element, a pair of opposed jaws depending from the sides of the element and mounted to move to and from one another into and out of gripping relation with a stack of sheets, and means for supporting the central portion of the stack against sagging and embodying an end hook, a supporting cable for the hook having one end thereof connected to said hook, a spring retracted drum carried by the element and having the other end of the cable attached thereto, and releasable mechanism controllable from one end of the lifter for locking the drum against rotation.

12. A lifter adapted for use in handling stacks of sheets and comprising a horizontally elongated supporting element, a pair of opposed jaws depending from the sides of the element and mounted to move to and from one another into and out of gripping relation with a stack of sheets, and means for supporting the central portion of the stack against sagging embodying an end hook, a supporting cable for the hook having one end thereof connected to said hook, and a spring retracted drum carried by the element and having a spiral groove of progressively increasing diameter around which the other end of the cable is wound.

13. A lifter adapted for use in handling stacks of sheets or other articles and comprising a horizontally elongated supporting element, a pair of opposed jaws depending from the sides of the element and mounted to move to and from one another, means supported by the element for shifting the jaws to and from one another, and means for supporting the stack of sheets to be lifted against sagging embodying an end hook, a supporting cable for the end hook having one end thereof connected to the hook, a spring retracted drum mounted on the central portion of

the element and having the other end of the cable attached to it, a pawl and ratchet for locking the drum against rotation, and means controllable from one end of the lifter for releasing the pawl.

5 14. A lifter adapted for use in handling stacks of sheets and other articles and comprising a horizontally elongated supporting element, a pair of opposed jaws disposed at the sides of the element and mounted to move to and from one another, means supported by the element for shifting the jaws to and from one another, a pair of hooks at the ends of the element for gripping and supporting the ends of the stack to be lifted, a pair of spring retracted drums mounted on the element and having pawls and ratchets for locking them against rotation, a pair of cables extending between the drums and the hooks, and means for conjointly releasing the pawls.

10 15. A lifter adapted for use in handling stacks of sheets and other articles and comprising a horizontally elongated supporting element, a pair of opposed jaws depending from the sides of the element and mounted to move to and from one another, means supported by the element for conjointly shifting said jaws, an end hook for gripping and supporting one end of the stack of sheets to be lifted, a spring retracted drum carried by the element and having a pawl and ratchet for locking it against rotation, a supporting cable for the hook having one end thereof anchored to the drum and the other end attached to the hook, means for releasing the pawl from the ratchet, a latch mechanism for automatically locking the pawl in its released position, and means for releasing said latch mechanism.

25 16. A lifter adapted for use in handling stacks of sheets and other articles and comprising a horizontally elongated supporting element, a pair of opposed jaws depending from the sides of the element and mounted to move to and from one another, means supported by the element for conjointly shifting said jaws, an end hook for gripping and supporting one end of the stack of sheets to be lifted, a spring retracted drum carried by the element and having a pawl and ratchet for locking it against rotation, a supporting cable for the hook having one end thereof anchored to the drum and the other end attached to the hook, means for releasing the pawl from the ratchet, a latch mechanism for automatically locking the pawl in its released position, and means manipulable from either end of the lifter for releasing said latch mechanism.
